DESIGN FOR A PRIE DIEU

William F. Liska, Chicago, Ill., assignor to Holland Brass Works, Incorporated, Chicago, Ill., a corporation of Illinois

Application January 15, 1936, Serial No. 60,583

Term of patent 7 years

To all whom it may concern:

Be it known that I, William F. Liska, a citizen of the United States, residing at Chicago, in the county of Cook and State of Illinois, have invented a new, original, and ornamental Design for a Prie Dieu, of which the following is a specification, reference being had to the accompanying drawing, forming a part thereof.

Referring to the drawing:

Fig. 1 is a front elevational view of a prie dieu showing my new design; and

Fig. 2 is a side elevational view thereof with the fringe omitted.

I claim:

The ornamental design for a prie dieu, as shown and described.

WILLIAM F. LISKA.
